[57] ABSTRACT

Brush having adjustable bristle hardness includes a bristle plate having a multiplicity of bristle brushes extending from one side thereof; a perforated plate located on the one side of the bristle plate and formed with a multiplicity of perforations through which the bristle brushes, respectively, extend; a cover member located on the other side of the bristle plate; an adjusting wheel disposed between the bristle plate and the cover member; and threaded connecting means extending between the perforated plate and the adjusting wheel and cooperable with the latter for adjustably spacing the perforated plate and the bristle plate at varying distances from one another.

MAGNETIC CORE MEMORY

BACKGROUND OF THE INVENTION

This invention relates to magnetic core memory stacks, and more particularly to an improved structure for core planes of a stack.

A typical magnetic core memory is comprised of a stack of toroidal core planes. In each plane, the cores are arranged in rows and columns. Each core is oriented at 45° with respect to the rows and columns to facilitate threading the cores with conductors along the rows and columns and as well as long diagonal paths if desired. For example, in a typical coincident current core memory, each plane consists of a matrix of toroidal cores arranged in rows and columns. All cores in a given row are threaded by a common conductor to provide a single turn winding through each core. Similarly all cores in a given column are threaded by a common conductor. The two sets of conductors are referred to as the X and Y drive windings.

To store a binary 1 in a selected core of a given plane, the X and Y drive windings which cross at the selected core are each driven with a current pulse of half the amplitude necessary to set the core to the one state. All of the other cores wired by the energized X and Y drive windings are disturbed, but not set to the one state since each is subjected to a magnetomotive force of only half the value necessary to set it to the one state. To read a binary digit stored in a selected core, the X and Y drive windings which cross at the selected core are each driven with a current pulse of half the amplitude required to change the state of the selected core to that opposite the binary-1 state. A third winding (Z) passing through all of the cores of the plane diagonally senses a binary 1 being read from the selected core. A fourth winding (I) passing through all of the cores in the plane in a direction parallel to the X or the Y winding is used to selectively inhibit the storage of a binary 1 in a core of a selected plane.

Other patterns for threading cores with conductors have been employed for magnetic core memories of different types, such as the linear-select type, or what has come to be known as a 2 1/2 D type. For each type, it is common practice to stand the cores of a plane on end, and to orient them at 45° to the rows and columns in a box or herringbone pattern to facilitate threading the cores along the rows and columns, and sometimes along a diagonal, as in the case of a typical four-wire, coincident-current core memory.

The practice has been to arrange the cores into the desired array pattern by placing a handful of cores (typically 10 to 20 mils in diameter) on a plate in a tray. The plate has slots in the desired pattern so that as the tray is vibrated, the cores fall into the slots. The slots are narrow, but almost as deep as the core diameter. For example, using a 20-mil core, the slots may be 18 mils deep so that when a core falls into a slot, it stands on end and protrudes sufficiently for a sheet of flexible material with an adhesive film to be used to remove the array of cores from the plate. Once a core has fallen into every slot in the tray, any excess cores are removed and the adhesive sheet is pressed against all of the cores. By carefully turning the plate upside down on a work table or board, and then carefully lifting the plate, the desired core array pattern is left adhesively affixed to the sheet with each core standing on end. The array is then transferred to a substrate coated with a suitable

adhesive, such as RTV, a silicone rubber compound produced by the General Electric Company, or a lacquer. That is done by placing the adhesive sheet on the substrate with the cores pressed against the adhesive on the substrate. Then the adhesive plate is peeled off. Any cores which do not stay on the substrate must be replaced and aligned by hand, a difficult task. The desired windings through the cores are then provided. Core memory planes thus individually formed are placed on supporting printed-circuit boards, or the like, through which connections are made to the core windings. The completed memory plane boards are then stacked to provide a magnetic core memory of the desired size.

A magnetic plate is sometimes used instead of an adhesive sheet to lift the array of cores from the slots in the vibrating-tray plate. The array is then transferred to a substrate as before. An advantage of this technique is that cores are less apt to fail to adhere to the substrate, but a disadvantage is that if one core tilts too much, an unbalanced field is produced which will cause it to tilt further until it falls against an adjacent core. That further disturbs this field and quite often an entire row of cores will fall like a row of dominoes. For this reason, magnetic plates are not often used as a transfer vehicle.

SUMMARY OF THE INVENTION

An object of this invention is to provide a slotted plate which may be used on a standard vacuum vibrator for arranging cores in a desired array pattern, and thereafter used as a substrate for the array while threading cores with desired windings.

Another object of this invention is to provide an improved structure for a plane in a magnetic core memory using a slotted plate to support the cores, and to provide a method of fabricating such a plate.

Briefly, in accordance with one aspect of the present invention, a slotted plate is fabricated out of a sheet of plastic or other nonmagnetic material. The sheet is masked using photo resist techniques and then chemically etched to produce the desired pattern of slots. The slot pattern of the mask is virtually identical with a plan view of the desired core array. Only the size of the slots in width and length deviates from the thickness and outside diameter of the cores, and the deviation is preferably that of smaller dimensions. This chemical etching produces slots with walls which are invariably tapered to permit capture of toroidal cores on a vacuum vibrator, but not allow the cores to pass through the slots. Before using the etched plate on a vacuum vibrator, the resist is removed from the plate.

After cores have been vacuum vibrated into proper position in all slots, a gentle mist of an adhesive is sprayed over the cores to hold them in place without obstructing the apertures of the cores. Then a heavier layer of adhesive is applied between the cores and the plate from the side opposite the cores, again without obstructing the core apertures, preferably by cementing the core plate to a substrate which may be a printed circuit board or frame assembly plate, through which connections are made to windings threaded through the cores. The cores may be threaded either before or after the slotted plate is cemented to the substrate, but preferably afterwards. Then the adhesive sprayed over the cores may be removed with a solvent before thread-

Other features which are considered as characteristic for the invention are set forth in the appended claims.

Although the invention is illustrated and described herein as embodied in brush having adjustable hardness, it is nevertheless not intended to be limited to the details shown, since various modifications and structural changes may be made therein without departing from the spirit of the invention and within the scope and range of equivalents of the claims.

The construction and method of operation of the invention, however, together with additional objects and advantages thereof, will be best understood from the following description of specific embodiments when read in connection with the accompanying drawings, in which:

FIG. 1 is an exploded elevational view, partly in section, of the brush having adjustable hardness, constructed in accordance with the invention; and

FIG. 2 is a bottom plan view of the cover member of FIG. 1.

Referring now to the drawing, there is shown therein the brush constructed in accordance with the invention which has four main parts including a cover member 1, a bristle plate 2, a perforated plate 3 and an adjusting wheel 4 that are sandwiched together. The perforated plate 3 is provided with four guide pins 6 guidingly extending through openings 18 formed in the bristle plate 2 and into bored recesses formed in the cover member 1. By turning the adjusting wheel 4, the perforated plate 3 is raised or lowered, as viewed in FIG. 1, so that a desired length s of the bristles 7 can be adjusted to. The raising or lowering of the perforated plate 3 is achieved by means of a slide projection 15 extending radially inwardly within a hollow shaft 14 secured to the adjusting wheel 4, the slide projection 15 engaging in the thread groove 17 formed on the threaded pin 16 which is substantially centrally secured to the perforated plate 3. A depression 20 is formed in the cover member 1 having a larger diameter than the width of the brush handle part at the top of the cover member 1 so that a recess 5 is formed on both lateral sides of the cover member 1 through which the adjusting wheel 4 protrudes. The recess 5 formed in the cover member 1 becomes even larger if an elongated indentation 21 is provided in the cover member 1. This indentation 21 is registerable with a corresponding indentation 21 formed in the bristle plate 2, forming together a groove which ensures a better manipulation and gripping of the brush. As a bearing for the adjusting wheel 4, a recess 13 is formed in the cover member 1 wherein there is fitted a pin 12 formed at the upper surface of the adjusting wheel 4. Locking of the perforated plate 3 in a desired position is achieved by a knurl or small teeth 8 and 9 which are located, respectively, at the underside of the adjusting wheel 4 and at a raised annular area formed on the upper side of the bristle plate 2. To limit the rotation of the adjusting wheel 4, respective mutually engageable limit pins 10 and 11 are provided at the underside of the adjusting wheel 4 and at the upper side of the bristle plate 2.

I claim:

1. Brush having adjustable bristle hardness, comprising a bristle plate having a multiplicity of bristle brushes extending from one side thereof; a perforated plate located on said one side of said bristle plate and formed with a multiplicity of perforations through

which said bristle brushes, respectively, extend; a cover member located on the other side of said bristle plate; an adjusting wheel disposed between said bristle plate and said cover member and extending diametrically in a plane substantially perpendicular to said bristle brushes; and threaded connecting means extending between said perforated plate and said adjusting wheel and cooperable with the latter for adjustably spacing said perforated plate and said bristle plate at varying distances from one another.

2. Brush according to claim 1 wherein said threaded connecting means comprises a threaded pin secured substantially centrally to said perforated plate and extending through a substantially central opening formed in said bristle plate, and a hollow shaft secured to said adjusting wheel and formed with a radially inwardly extending slide projection, said threaded pin being received in said hollow shaft, said slide projection being slidably received in the thread formed on said threaded pin, and said adjusting wheel being turnable so as to transmit an adjusting force through said slide projection to said threaded pin.

3. Brush according to claim 1 wherein said adjusting wheel is received in a depression formed in said cover member and has a diameter greater than the width of the brush.

4. Brush according to claim 1 wherein said adjusting wheel is provided with a pin located at a side thereof opposite the hollow shaft secured thereto, said pin of said adjusting wheel engaging in a corresponding recess formed in said cover member and forming a bearing for said adjusting wheel.

5. Brush according to claim 1 wherein said adjusting wheel has a diameter at least equal to the width of the brush.

6. Brush according to claim 1 including mutually engaging serrations formed on said adjusting wheel and said bristle plate.

7. Brush according to claim 6 wherein said serrations comprise a knurl formed on the side of said adjusting wheel facing said bristle plate, and a knurl formed on the opposing side of said bristle plate.

8. Brush according to claim 7 wherein said knurl of said adjusting wheel is provided within a depression formed in said adjusting wheel, and said knurl of said bristle plate is formed on a raised annular surface of said opposing side of said bristle plate.

9. Brush according to claim 1 wherein one rotation of said adjusting wheel corresponds to maximum adjustable distance between said perforated plate and said bristle plate.

10. Brush according to claim 1 wherein said cover member and said bristle plate are elongated and have lateral elongated sides formed with elongated indentations.

11. Brush according to claim 1 includes guide pins secured to said perforated plate and guidingly extending through corresponding openings formed in said bristle plate and into corresponding recesses formed in said cover member.

12. Brush according to claim 9 including mutually engageable limit pins located respectively on said bristle plate and said adjusting wheel for limiting rotation of said adjusting wheel.

Patent No. 3,803,663 Dated April 16, 1974
Inventor(s) Georg Weihrauch Page - 2

It is certified that error appears in the above-identified patent and that said Letters Patent are hereby corrected as shown below:

The invention relates to brush having adjustable bristle hardness and, more particularly, of such a brush having a brush body, a bristle plate, a perforated plate and a cover, the perforated plate being adjustable with respect to the bristle plate.

The purpose of providing a brush wherein the effective length of the bristles is adjustable, is especially to obtain greater stiffness of the bristles for certain specific operations and to combine the advantages of a brush having long bristles and a brush having short bristles. Such a brush can be used to advantage wherever a change from hard to soft bristles is desired during the use thereof, especially cloth brushes, massage brushes, brooms, hand-scrubbing or washing brushes, hair-brushes, toothbrushes and the like. Soft, delicate materials require, for example, more gentle handling than

Inventor(s) Georg Weihrauch Page - 3

It is certified that error appears in the above-identified patent and that said Letters Patent are hereby corrected as shown below:

a coarse material that has been greatly soiled and which calls for the use of thicker or shorter bristles for cleaning the same.

For slightly soiled skin, for example, a hard scrubbing or washing brush with long, soft bristle is preferred, but for cleaning very dirty hands, a brush with short, i.e. hard, bristles is required and demanded.

The adjustability of hardness of the effective lengths of bristles becomes important as the service life or durability of the bristle material is increased. Only when the quality of the synthetic fibers of which the bristles may be formed is high, is the additional cost of the adjusting mechanism justified, because the better cleaning effectiveness that is attained can thereby be used over a relatively longer period of time.

To achieve greater stiffness of the bristles it

Patent No. 3,803,663 Dated April 16, 1974
Inventor(s) Georg Weihrauch Page - 4

It is certified that error appears in the above-identified patent and that said Letters Patent are hereby corrected as shown below:

has been known heretofore to vary the effective length of the bristles by means of a perforated plate which is adjustably disposed between the brush body and a specific location of the bristle length.

It has been found to be a disadvantage of this heretofore known construction, that the mechanism for adjusting the bristle hardness or stiffness is too complicated and that the brush is unwieldy because of disturbing operating or serviceing parts thereof. Furthermore, the adjustment with the heretofore known mechanisms of this general type is either too easy so that it tends to shift just as easily, or is too difficult to effect, and a selected position of the perforated plate cannot be locked in.

It is accordingly an object of the invention to provide a brush having adjustable hardness which is

adjustable in the height thereof, which has an adjusting mechanism provided with a minimum number of parts and disposed, furthermore, inside the brush housing, leaving the brush handle region free of interfering parts. A further object of the invention is to provide such a brush which affords easy adjustment of the effective bristle length, while, simultaneously, providing for satisfactory locking of the selected operating position of the perforated plate with respect to the bristle plate.

With the foregoing and other objects in view, there is provided in accordance with the invention, brush having adjustable bristle hardness, comprising a bristle plate having a multiplicity of bristle brushes extending from one side thereof; a perforated plate located on the one side of the bristle plate and formed with a multiplicity of perforations through which the bristle brushes, respectively, extend; a cover member located on the other side of the bristle plate;
